US00D916056S

(12) **United States Design Patent** (10) **Patent No.:** **US D916,056 S**
Boyd et al. (45) **Date of Patent:** **** Apr. 13, 2021**

(54) **EARPHONE**(71) Applicant: **Apple Inc.**, Cupertino, CA (US)(72) Inventors: **Robert Boyd**, Los Angeles, CA (US); **Sean Stewart Corbin**, South Lake Tahoe, CA (US); **Duy P. Le**, Los Angeles, CA (US); **Guillaume Raoult**, San Francisco, CA (US); **Christopher Kuh**, San Francisco, CA (US); **Robert Brunner**, Glen Ellen, CA (US)(73) Assignee: **Apple Inc.**, Cupertino, CA (US)(***) Term: **15 Years**(21) Appl. No.: **29/721,503**(22) Filed: **Jan. 21, 2020****Related U.S. Application Data**

(63) Continuation of application No. 29/685,002, filed on Mar. 25, 2019, now Pat. No. Des. 897,320.

(51) **LOC (13) Cl.** ..... **14-01**(52) **U.S. Cl.**USPC ..... **D14/223**(58) **Field of Classification Search**

(57) CLAIM

The ornamental design for an earphone, as shown and described.

DESCRIPTION

FIG. 1 is a front perspective view of an earphone showing the claimed design;

FIG. 2 is a bottom front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the earphone that form no part of the claimed design.
